(57) **CLAIM**

The ornamental design for a power module housing, as
shown and described.

DESCRIPTION

FIG. 1 is a front perspective view of a power module
housing showing our new design;

FIG. 2 is a rear perspective view thereof;

FIG. 3 is a front view thereof;

FIG. 4 is a top view thereof;

FIG. 5 is a bottom view thereof;

FIG. 6 is a rear view thereof;

FIG. 7 is a right side view thereof; and,

FIG. 8 is a left side view thereof.

The broken lines are for illustrative purposes only and form
no part of the claimed design.
